UNITED STATES PATENT OFFICE.

JOHN F. ZIMMER, OF NEW YORK, N. Y.

TRANSPORTING AND DISPENSING RECEPTACLE.

1,286,484.

Specification of Letters Patent.

Patented Dec. 3, 1918.

Application filed June 16, 1916. Serial No. 104,032.

To all whom it may concern:

Be it known that I, JOHN F. ZIMMER, a citizen of the United States, residing at New York, in the county of New York and State 5 of New York, have invented certain new and useful Improvements in Transporting and Dispensing Receptacles, of which the following is a specification.

My invention relates to a transporting receptacle and it aims to provide an article of this nature which may be lifted while retaining its contents and which may also be lifted by a separate means so as to effect dispensation of its contents; to provide a receptacle of this nature which may be emptied without the usual tilting operation; to provide a receptacle of this character having a gravity-opening bottom closure with a receptacle lifting and transporting 10 handle connected thereto and with an additional lifting handle independent of the said closure so that in the event the receptacle is lifted by the last mentioned means, the closure will open and the contents of the receptacle will escape, and to provide a device of the construction hereinafter set forth possessing the additional objects and advantages pointed out in relation thereto as the description progresses, and which is to be 15 taken in connection with accompanying drawings illustrating one preferred embodiment.

In said drawings;—

Figure 1 is a perspective view of a pail 35 or receptacle constructed in accordance with my invention;

Fig. 2 is a vertical sectional view through the article of Fig. 1, showing in dotted lines the closure in its downward or open position and

Fig. 3 is an enlarged detail cross sectional view illustrating the method of connecting the main handle to the bottom closure of the pail.

Referring specifically to the drawings, wherein like reference characters designate like or similar parts, a conventional receptacle is shown in the form of a pail which may be provided with one or more lifting handles 5, and preferably two, being dis-

posed at diametrically opposite points and exteriorly of the receptacle.

The major portion of the bottom of the receptacle is a closure member 6 adapted to swing downwardly from a pivot 7 and which is maintained in place by lugs 8 bent there-around and alternately provided on the closure and the remainder of the receptacle bottom. The closure 6 preferably has an upwardly extending flange at its marginal edge 9 which is overlapped by a flange 10 provided interiorly of the receptacle body 4 adjacent the base. This construction will minimize danger of escape of the contents of the receptacle prematurely. Extending 15 radially from the closure 6 at diametrically opposite points are pivot lugs 11 to which the terminal ends 12 of a U-shaped handle 13 straddling the receptacle are pivoted. These pivot members 11 when the closure is 20 in closed position, are received in notches or cut out portions 14 extending inwardly from the lower edge of the body 4. Guides 15 may be fastened to the pail body 4 on the exterior to co-operate with the arms of the 25 handle 13.

In use, as the receptacle is lifted by manual engagement with the handle 5, the closure 6, through gravity, will swing downwardly to the dotted line position of Fig. 2 30 and thus the contents may escape without the usual tilting action and as a result of mere raising. However, if it is desired that the contents should remain in the receptacle, it is lifted by means of the handle 13, which 35 being connected to the closure 6, prevents descending swinging movement thereof. Also when thus used, the co-operating flanges 9 and 10 prevent escape of the contents.

Since merely the preferred embodiment of 40 the invention has been illustrated and described, it is to be understood that changes in the details of construction may be resort-ed to within the spirit and scope of ap-pended claim.

I claim:

A receptacle having a gravity-opening closure pivoted thereto for downward swing-ing movement, overlapping flanges, one on the closure and one on the receptacle adja- 45 50 55 60 65 70 75 80 85 90 95 100

cent the closure, the U-shaped handle straddling the receptacle, pivot members extending from the closure, the receptacle at the base being cut away to receive said pivot members, the free ends of the handle being pivoted to said pivot members, and handle means independent of said closure.

In testimony whereof I affix my signature in presence of two witnesses.

JOHN F. ZIMMER.

Witnesses:

JAMES F. WALSH,
GEORGE ESELBRUN.
